UNITED STATES PATENT OFFICE.

CARL SCHREIBER, OF BRESLAU, GERMANY.

SUPPORT FOR BICYCLES.

SPECIFICATION forming part of Letters Patent No. 634,480, dated October 10, 1899.

Application filed November 15, 1898. Serial No. 696,494. (No model.)

To all whom it may concern:

Be it known that I, CARL SCHREIBER, a subject of the King of Prussia, German Emperor, residing in Breslau, Prussia, Germany, have 5 invented certain new and useful Improvements in Rests or Supports for Bicycles and other Vehicles, of which the following is a specification.

The present invention relates to a mechanism for cycles and similar vehicles which enables the rider while seated upon the saddle to come at any time to a full stop in the middle of the road and to proceed without alighting from the wheel. Besides it is possible 15 easily to mount on and to dismount from the cycle when supported by the said mechanism. The latter consists of two supporting-rod 20 which are arranged on both sides of the cycle, and when the latter travels are locked in their upper position to the cycle-frame. When stopping the cycle, these supporting-rod may be unlocked by operating a special mechanism, so that the said rods sink down until they are in contact with the road, in which 25 position they are automatically locked. The locking of the supporting-rod in their lower position of use is effectuated by toothed 30 wheels connected to the axle of the driving-wheel. These toothed wheels gear with racks of the supporting-rod and, when starting 35 the cycle, lift up automatically the supporting-rod so much that the device serving for locking them in their upper position falls in.

The invention will be fully understood from 35 the detailed description hereinafter presented, reference being had to the accompanying drawings, in which—

Figure 1 is a side view, and Fig. 2 a partial 40 rear end view, of a cycle furnished with the new mechanism. Fig. 3 is a rear view, on an enlarged scale, of the fork of the rear wheel with the supporting-rod and the means for holding and releasing them. Fig. 4 is a side view of the mechanism for locking and unlocking the supporting-rod. Fig. 5 is a side 45 view of the mechanism for locking the supporting-rod in their lower position and for lifting them up automatically when the rider proceeds. Fig. 6 is a front view of this mechanism; and Fig. 7, an upper view of the same, 50 partly in section.

On both sides of the fork *a* of the driving-

wheel supporting-rod *b*, with rollers *b'*, are arranged in rings *c* of the cycle-frame, so that they can slide in these rings, Figs. 1 and 55 2. These supporting-rod are locked in their upper position by spring-actuated lock-bolts *d*, which can be retracted from the respective openings *d'* of the supporting-rod *b* by two levers *f*, which can be drawn together by 60 means of a double hook *e*, Figs. 3 and 4.

Near the axle of the driving-wheel on each side of the cycle is arranged a locking device, which serves to lock the supporting-rod in their lower position, Figs. 5 to 7. This device consists of a slide *g* and a spring-actuated locking-bolt *h*, which is retained by a hook-shaped arm *g'* of this slide and when released by this arm falls into openings *h'* of the respective supporting-rod *b*, so as to lock 70 it in its lower position as long as the mechanism for unlocking the bolts *d* is worked. After having released the said mechanism a toothed wheel *i*, fixed to the axle of the driving-wheel and gearing with a rack *i'* of 75 the respective supporting-rod *b*, locks this rod against upward movement and serves also the purpose to raise the supporting-rod up to its upper position. In order to prevent the wheel *i* from gearing with the rack *i'* during the downward movement of the supporting-rod, the rack *i'* is connected to the supporting-rod by arms *i*², and is, when the mechanism for unlocking the bolts *d* is worked, 80 displaced by means of a beveled lug *g*² of the 85 slide *g* in such a manner that the supporting-rod *b* connected with it turns in the rings *c*, thus removing the rack *i'* from the toothed wheel *i*, so that the supporting-rod descends without being checked. 90

The operation of the mechanism is as follows: When it is desired to stop the cycle without dismounting from it, the rider simply by pulling on a cord or a chain moves down the slide *g* and the double hook *e*, the latter being held in its upper position by a strong spring *e'* and being connected to the slide *g* by a cord or a chain. By this operation the ends of the double hook *e*, which slide in slots *f'* of the levers *f*, draw together 100 the levers *f*, whereby the latter withdraw the bolts *d* from the openings *d'*, so that the supporting-rod *b* can slide down in the rings *c*. At the same time by the downward move-

ment of the slide g the lugs g^2 push forward the spring-actuated sleeves g^3 , so that the racks i' are disengaged from the toothed wheels i and descend together with the supporting-rods b . When descending, the hook-shaped arms g' of the slides g release the spring-actuated lock-bolts h by allowing the lugs h^2 , Figs. 6 and 7, of them to enter the curved parts g^4 of the arms g' . The said lock-bolts h lean against the supporting-rods b , and the openings h' arranged in the latter slide over the rounded upper edges of the bolts h until the rollers b' touch the road. When, however, the supporting-rods are reascended by the cycle being thrown over sidewise, the lock-bolts h , the lower edges of which are not rounded, spring in the openings h' and lock the supporting-rods against further ascending. When the rider, after having stopped the cycle, releases the cord serving to operate the mechanism, the spring e' draws up the double hook e and the slide g . By this movement the levers f are spread and the lock-bolts d are released, so that by the action of their springs they are pushed against the supporting-rods b . At the same time the ascending hook-shaped arms g' withdraw the lock-bolts h from the respective openings h' of the supporting-rods, and the sleeves g^3 , now released by the lugs g^2 , are withdrawn by their springs. By these means the racks i' are thrown into gear with the toothed wheels i , which now lock the supporting-rods b against reascending. When the rider desires to proceed, a special operation for releasing the mechanism is not necessary, for the toothed wheels i , fixed to the axle of the driving-wheel, when the latter is rotated raise automatically the supporting-rods b until the openings d' of them are opposite the ends of the lock-bolts d . The ends of these lock-bolts d are preferably cone-shaped, so that when entering the openings d' they raise the supporting-bars b still a sufficient distance to bring the lowest tooth of each rack i' out of contact with the respective toothed wheel i , thus avoiding the wear and tear of these parts while traveling.

Having now described my invention, what I claim is—

1. In a cycle a pair of supporting-rods extending downward one on each side of the rear wheel and sliding in guides attached to

the cycle-frame, bolts for locking the said rods in their upper position, means for unlocking these bolts to allow the supporting-rods to slide down until their ends shall be in contact with the road, toothed wheels connected with the axle of the rear wheel serving for locking engagement with the racks of the supporting-rods in their lower position and for reascending the latter when restarting and means for disengaging the racks and the toothed wheels during the descending of the supporting-rods, substantially as described.

2. In combination with the cycle, the supporting-rods extending downward one on each side of the cycle, the bolts for locking the supporting-rods in their upper position, a suitable mechanism for unlocking these bolts, the toothed wheels connected with the axle of the rear wheel, serving for locking engagement with racks of the supporting-rods in their lower position, a slide connected with the before-mentioned unlocking mechanism and bolts for locking the supporting-rods in their lower position until the racks and the toothed wheels have been thrown into gear, the last-mentioned lock-bolts being released by the slides when the unlocking mechanism is worked and being unlocked when this mechanism is at rest; substantially as set forth.

3. In combination with the cycle the supporting-rods extending downward one on each side of the cycle, the bolts for locking the supporting-rods in their upper position, the mechanism for unlocking these bolts, the toothed wheels connected with the axle of the rear wheel serving for locking engagement with racks of the supporting-rods in their lower position, the slide connected with the before-mentioned unlocking mechanism and sleeves surrounding the racks coöperating with cam-lugs of the slides for the purpose of disengaging the racks and the toothed wheels when the unlocking mechanism is worked; substantially as set forth.

Signed at Breslau, Province of Silesia, Empire of Germany, this 31st day of October, 1898.

CARL SCHREIBER.
